United States Patent Office

Des. 177,711
Patented May 22, 1956

177,711

WINDSHIELD

Stanley A. Blumberg, Baltimore, Md.

Application October 19, 1955, Serial No. 38,450

Term of patent 14 years

(Cl. D14—6)

Fig. 1.

Fig. 2.

Fig. 1 is a perspective view of the windshield showing my new design; and

Fig. 2 is a top plan view of the windshield shown in Fig. 1.

The fragmentary dotted line showing of an automobile in Figure 1 is only disclosed for purpose of illustration.

I claim:

The ornamental design for a windshield, as shown and described.
